UNITED STATES PATENT OFFICE.

JOHN R. BARLOW, OF PIEDMONT, ALABAMA.

ADJUSTABLE THREAD GUIDE AND SLUB CATCHER.

Application filed November 2, 1923. Serial No. 672,398.

To all whom it may concern:

Be it known that JOHN R. BARLOW, a citizen of the United States of America, residing at Piedmont, in the county of Calhoun and State of Alabama, has invented new and useful Improvements in Adjustable Thread Guides and Slub Catchers, of which the following is a specification.

The purpose of the invention is to provide an adjustable thread guide and slub catcher for spinning and doubling or twister frames for the purpose of catching slubs, accumulations or other enlargements or imperfections in the yarn, thus resulting in the break in the yarn at the point of imperfection and necessitating the care and neat piecing of the yarn in order to pass through the guide, thereby insuring good workmanship at this point.

It is to be understood that the particulars herein given are in no way limitative and that, while still keeping within the scope of the invention, any desired modifications of detail and desired proportions may be made in the apparatus according to the circumstances.

The invention comprises further features and combinations of parts to be hereinafter set forth, shown in the drawings and claimed.

In the drawings:

Figure 1 is a view partly in elevation and partly in section of a portion of a spinning machine frame of conventional construction, showing the application of the thread guide.

Figure 2 is a sectional view on line 2—2 of Figure 3.

Figure 3 is a perspective view of the thread guide constructed in accordance with the invention.

Figure 4 is a bottom plan view thereof.

Figure 5 is a view partly in elevation and partly in section of a twister machine frame showing the application of a modified construction of thread guide.

Figure 6 is a sectional view on line 6—6 of Figure 8.

Figure 7 is an end elevation of the thread guide.

Figure 8 is a top plan view of the thread guide shown in Figure 5.

Figure 9 is a bottom plan view of the thread guide shown in Figure 7 and 8.

The invention is designed to take the place of the ordinary thread guide used on spin-

ning and twister frames, being illustrated in connection with the latter and interposed between the bobbin 1 and the delivery rolls 2 over which the strands of thread 3 pass from the spools 4. The guide comprises a U-shaped body portion 5 with which is formed the shank 6, the latter being received in a socket formed in the thread board 7 and removably secured in the latter by a set-screw 8. Formed as integral parts with the legs of the U-shaped body portions 5 are the leaves 9 directed inwardly towards each other to define an intervening slot 10 through which the strands of thread pass, one of the legs of the U-shaped members being formed with a finger 11 disposed transversely of the U-shaped member and directed rearwardly of the latter, lying in a plane slightly above the plane of the upper faces of the leaves 9. A horn 12 is formed as an integral projection from the opposite leg of the U-shaped member and lies in the plane of the latter. The horn 12 and finger 11 constitute cooperative means by which the strands of thread may be directed into the slot 10 in the event that there is a break and the strands have to be pieced, the finger 11 also serving as a closure for the end of the guide slot to retain the strands of thread in the latter.

The legs of the U-shaped member have a spring tendency away from each other so that normally there is a tendency to widen the slot 10. In order that the width of the slot may be reduced to suit the conditions of the work in hand, however, the legs of the U-shaped member are spanned by a bolt 13, the head of which abuts the outer face of one leg, the nut 14 being engaged with the threaded extremity of the bolt and abutting the outer face of the other leg. The turning of the bolt will tend to draw the legs towards each other and thus reduce the width of the slot. The nut 14 acts as a jamb nut to hold the legs set. By this means the width of the slot may be adjusted to suit the diameter of thread being passed by the guide and in the event of an enlargement or increase of diameter of the thread at a certain point which would result in imperfect yarn, the enlargement will impinge on the leaves, thus causing a break in the thread at this point. In view of the fact that the width of the slot is fixed by the proper adjustment, the piecing of the thread must be made with such care

and accuracy that it will pass through the slot after the piecing has been made.

Referring more particularly to Figures 4 to 7, inclusive, it will be noted that there are disclosures of a modified construction of the thread guide and slub catcher. As in the thread guide and slub catcher illustrated in Figures 1 to 3, the modified construction includes a shank which enters a socket in a support 7^a in the spinning frame, being removably secured to the socket by means of a set-screw 8^a. The other end of the shank terminates in a disk or segment 17 in the periphery of which a circular recess 18 is formed. One edge of this recess is beveled off or countersunk and has a polished surface in order to readily guide the thread therethrough. This recess is formed at a location substantially opposite the shank 20 where it connects with the disk or head. Projecting from the disk in close position to the recess 18 is a lug 19 which acts as a guard for the thread, also as a guide for directing the thread toward and into the recess 18. The edge of the lug or guard is substantially in alinement with one edge of the shank and projecting from one edge of the disk adjacent the lug is an arcuate tongue 20 which terminates in a horn 21. The horn is straight in a direction at right angles to the disk and projects from the arcuate tongue in a plane parallel with the face of the disk.

Secured on one face of the disk which is carried by the shank is an additional disk 22. A screw passes through the disk 22 and is threaded into the disk 17. This screw 23 may be loosened or tightened whereby the disk 22 may be adjusted. The disk 22 has adjacent its edge a plurality of slots 24. These slots are constructed of various widths, depending entirely on the size of the yarn which passes through them. In the operation, the disk 22 is adjusted so that one edge of either one of the slots 24 may be disposed in a plane with the plane of one edge of the lug which is adjacent the circular recess. The horn 21 is disposed so that its edge portion 25 will lie across one of the slots of the disk 22, it depending entirely upon the adjustment of the disk. In fact, the edge 25 of the horn assumes a position substantially half way between the open end and the crotch of the slot and the horn 55 beyond this point merges into an arcuate portion 26 which is concentric with the center of the disk 22. At a point a little beyond the arcuate portion 26, the horn terminates in an extension 27 which is curved 60 in a direction opposite to the curvature of the arcuate portion 26. This curved extremity 27 acts to guide the thread between the curved portion of the horn and the disk

22 whereby the thread may enter the slot which may be disposed adjacent the edge 65 25 of said lug. When the thread is guided to this position, it will engage the slot and should there be any slubs or enlargements in the thread, during its passage from the bobbin to the spinning mechanism and thence to the spools, the thread may or may not break, it depending entirely upon the tension on the thread during its passage from the bobbins. The edge 25 of the lug acts to direct the thread into the slot which may be disposed adjacent the edge 25. However, should the thread break, it may be subsequently pieced or spliced, the splice being of such size as to pass through the slot readily during its passage from the bobbins to the spinning mechanism and thence to the spools of the spinning machine. By loosening the screw which fastens the disk 22 to the disk 17, the disk 22 may be adjusted so as to be disposed in one of the slots in the proper position to receive the thread. Should the thread to operate through the spinning machine be increased in diameter, a larger slot may be disposed to permit of the passage of the thread and should a smaller thread be used on the spinning machine, the disk may be adjusted to arrange a smaller slot in position for the reception of the thread.

The invention having been described, what is claimed is:

1. The combination with a spinning machine of a thread guide and slub catcher interposed between the bobbins and the spinning mechanism, said guide having a slot and a guide lug adjacent thereto, and a horn or projection overlying the slot and spaced from the face of the guide for directing a thread toward and into engagement with the slot. 100 105

2. The combination with a spinning machine, of a thread guide and slub catcher comprising a disk provided with a guide lug, a member adjustably secured on the disk and provided with a slot adjacent to the guide lug, and a projection overlying the slot for guiding a thread toward and into engagement with the slot. 110

3. The combination with a spinning machine, of a thread guide and slub catcher interposed between the bobbin and the spinning mechanism, said thread guide and slub catcher comprising a member, an element secured on the member and having a guide space, and a horn overlying the guide space and spaced relatively close to the element for directing the thread toward and into the space. 115 120

In testimony whereof he affixes his signature.

JOHN R. BARLOW,
